The ornamental design for a desktop with concave pull-out tray, as shown and described.

DESCRIPTION

FIG. 1 is a right front perspective view of a desktop with concave pull-out tray showing my new design;

FIG. 2 is a left front perspective view thereof with the tray in the pulled-out position;

FIG. 3 is a left side elevational view thereof, the right side being a mirror image thereof;

FIG. 4 is a front elevational view thereof; and,

FIG. 5 is a top view of the design shown in FIG. 1.

The views are shown broken away to indicate indeterminate length. The portion of the lower shelf not shown in FIGS. 1, 2 and 3 are not part of the claimed design.

The bottom and rear views of the design are not shown and form no part of the claimed design. The dashed lines represent environmental elements only and form no part of the claimed design.
